UNITED STATES PATENT OFFICE.

KARL PRINZ ZU LÖWENSTEIN, OF NECKARGEMÜND, AND FRITZ HAUFF, OF STUTTGART, GERMANY, ASSIGNORS, BY MESNE ASSIGNMENTS, TO THE CHEMICAL FOUNDATION, INC., A CORPORATION OF DELAWARE.

METHOD OF PRODUCING NITROGEN-CONTAINING COMPOUNDS.

1,386,941.

Specification of Letters Patent. Patented Aug. 9, 1921.

No Drawing.

Application filed August 18, 1916. Serial No. 115,733.

To all whom it may concern:

Be it known that we, KARL PRINZ ZU LÖWENSTEIN and Dr. FRITZ HAUFF, residing at Neckargemünd, Germany, and Stuttgart, Germany, have invented certain new and useful Improvements in Methods of Producing Nitrogen-Containing Compounds, (for which we have filed an application in Germany July 23, 1915,) of which the following 10 is a specification.

The present invention relates to the utilization of methane or gases of the methane series in the formation of cyanids or cyanamids.

15 The methane or the like is highly heated and thereby dissociated into pure carbon and pure hydrogen.

The carbon is mixed or briqueted with an alkaline salt, for instance, barium carbonate 20 or other barium salt.

The hydrogen is burned in atmospheric air and the nitrogen of the air thereby heated without the application of external heat. The resulting mixture is cooled until 25 the steam produced by the combustion is precipitated leaving the nitrogen free.

The nitrogen is forced in heated condition

through a revolving furnace in which the mixture briquets are carried, whereupon the nitrogen combines with the carbon of the 30 mixture, at about 1200 to 1400° Celsius, forming cyanids or cyanamids.

We claim as our invention:—

A process comprising dissociating the hydrogen and pure carbon of a gas of the 35 methane series; mixing said pure carbon with an alkaline salt; burning said hydrogen in atmospheric air, thus producing a mixture of steam and nitrogen; bringing said nitrogen in contact with the aforesaid 40 mixture of pure carbon and an alkaline salt, and combining the nitrogen with said carbon and said salt to form cyanids or cyanamids.

In testimony whereof we affix our signatures in presence of witnesses.

KARL PRINZ ZU LÖWENSTEIN.

Witnesses as to Karl Prinz zu Löwenstein:

HENRY HASPER,

ALLEN F. JIMNYS.

DR. FRITZ HAUFF.

Witnesses as to Dr. Fritz Hauff:

ERNEST ONIONMANY,

EUGEN SCHLEICHER.
